DESIGN FOR A HELICOPTER

Michael E. Gluhareff, Bridgeport, Conn., assignor to United Aircraft Corporation, East Hartford, Conn., a corporation of Delaware

Application August 13, 1948, Serial No. 148,098

Term of patent 3½ years

(Cl. D71—1)

To all whom it may concern:

Be it known that I, Michael E. Gluhareff, a citizen of the United States, residing at 579 Clinton Avenue, Bridgeport, in the county of Fairfield and State of Connecticut, have invented a new, original, and ornamental Design for a Helicopter, of which the following is a specification, reference being had to the accompanying drawing, forming a part thereof.

Fig. 1 is a top plan view of a helicopter, showing my new design.

Fig. 2 is a side elevational view.

Fig. 3 is a front elevational view.

Fig. 4 is a perspective view.

I claim:

The ornamental design for a helicopter, substantially as shown.

MICHAEL E. GLUHAREFF.
